UNITED STATES PATENT OFFICE.

CHARLES C. TOMKINSON, OF PLAINFIELD, NEW JERSEY, ASSIGNOR TO J. EDWARD OGDEN, OF MOUNTAINVILLE, NEW YORK.

EXPANSION SHIELD.

Application filed December 6, 1924. Serial No. 754,285.

This invention relates to improvements in expansion shields of the character employed for obtaining anchorage in walls of brick, stone and cementitious material not adapted to directly receive a threaded member.

The invention more particularly relates to expansion shields of the "drive-in" type.

One of the objects of the invention is to provide an expansion shield that can be economically manufactured and will effectively perform the desired functions.

Another object of the invention is to provide an expansion shield adapted to be used with and expanded by a driven expanding element such, for instance, as a nail.

Further objects of the invention will appear from the following specification taken in connection with the drawings, which form a part of this application, and in which

Fig. 1 is an elevational view of one form of expansion shield constructed in accordance with the invention.

Fig. 2 is an elevational view taken at right angles to Fig. 1.

Fig. 3 is an elevational view of the shield shown in Fig. 1, this view being taken 180° from the view shown in Fig. 1.

Fig. 4 is a bottom plan view of the construction shown in Fig. 2.

Fig. 5 is a top plan view of the structure shown in Fig. 2.

Fig. 6 is a transverse sectional elevation taken substantially on line 6—6 of Fig. 2.

Fig. 7 is an elevational view of another form of shield constructed in accordance with the invention.

Fig. 8 is an elevational view taken at right angles to Fig. 7.

Fig. 9 is an elevational view similar to Fig. 7, but showing the opposite side elevation of the shield.

Fig. 10 is a bottom plan view of the shield shown in Fig. 8.

Fig. 11 is a top plan view of the construction shown in Fig. 8.

Fig. 12 is a transverse sectional elevation taken substantially on line 12—12 of Fig. 8.

Fig. 13 is an elevational view of another form of shield constructed in accordance with the invention.

Fig. 14 is an elevational view taken at right angles to Fig. 13.

Fig. 15 is an elevational view similar to Fig. 13 but showing the opposite side of the shield in elevation.

Fig. 16 is a bottom plan view of the structure shown in Fig. 14.

Fig. 17 is a top plan view of the structure shown in Fig. 15.

Fig. 18 is a transverse sectional elevation taken substantially on line 18—18 of Fig. 14.

Fig. 19 is an elevational view of another shield constructed in accordance with the invention.

Fig. 20 is an elevational view taken at right angles to Fig. 19.

Fig. 21 is an elevational view showing the opposite side of the shield shown in Fig. 19.

Fig. 22 is a bottom plan view of the construction shown in Fig. 20.

Fig. 23 is a top plan view of the structure shown in Fig. 20.

Fig. 24 is a transverse sectional elevation taken substantially on line 24—24 of Fig. 20, and

Fig. 25 is an elevation showing the shield shown in Figs. 7—12, expanded.

The invention briefly described consists of a shield having a plurality of longitudinally extending expandable portions and having laterally extending flanges at one end thereof. In the particular embodiments of the invention illustrated, the shield is formed of a single piece of wire bent to provide the longitudinally extending expandable portions and the laterally extending flanges. In certain forms of the invention, there are three laterally expandable portions and in other forms, there are two expandable portions, but it will be understood that the wire may be bent to form any desired number of expandable portions. The shield is so constructed and arranged that when an expanding element is driven thereinto, the expandable portions will be forced laterally into gripping engagement with the walls of the opening in which the shield is placed. Further details of the invention will appear from the following description.

In the form of the invention illustrated in Figs. 1 to 6 inclusive, the shield comprises a pair of longitudinally extending expandable sections 30 and 31. These sections are formed from a single piece of wire having its ends 32 and 33 disposed at the inner end of the shield and forming the base of the shield. The wire intermediate its ends is bent laterally to form the flanges 34 and 35 and the section 30 has its inner end formed as a loop 36. When an expanding element is driven

into the shield shown in Figs. 1 to 6, the longitudinally extending portions are forced laterally into gripping engagement with the wall opening.

- 5 In the form of the invention illustrated in Figs. 7 to 12 inclusive, the shield consists of a single piece of wire bent to form three longitudinally extending sections 40, 41 and 42, each of these sections comprising two 10 lengths of wire. The two ends of the wire are shown at 43 and 44, these ends being bent laterally as illustrated and being disposed within loops 46 and 47, which form the end flanges of the shield. The sections 40, 41 and 15 42 are formed by substantially parallel lengths of wire, the wire at the inner ends of the sections being bent back upon itself as shown at 48 to form loops.

- Briefly stated, the wire is bent as follows. 20 One end of the wire is bent laterally as, for instance, at 43 and the wire is then bent back upon itself to form a loop 48 and the wire bent back on itself is substantially parallel to the first section and looped to form the 25 second section 42 of the shield. Then the wire is bent to form the flange 47 and is bent to form the two parallel lengths of the section 41, the end of the wire being bent laterally as shown at 44.
- 30 When an expanding element is driven into the shield shown in Figs. 7 to 12 inclusive, the three sections are forced radially and laterally into gripping engagement with the wall opening.

- 35 The shield of Figs. 7-12 is shown in Fig. 25 as expanded. It will be noted that the engagement of the expanding element or nail 65 with the loops 48 has forced the loop ends outwardly, thus increasing the gripping action of the shield.

- The shield shown in Figs. 13 to 18 inclusive also comprises three sections 50, 51 and 52. In this form of the shield, the two ends of 45 the wire are bent laterally and substantially parallel to each other as shown at 53 to form one of the flanges. The wire is then bent to form three elongated longitudinally extending loops or sections 50, 51 and 52 and flanges 54 and 55 are formed by bending laterally the 50 loops at the outer ends of the sections.

- When an expanding element is driven into the shield shown in Figs. 13 to 18, the three sections are forced radially and laterally into gripping engagement with the wall opening.

- 55 The shield shown in Figs. 19 to 24 inclusive is formed of flat wire instead of round wire as in the preceding forms. In this embodiment, the two ends 60 and 61 are bent laterally to form flanges and a flange 62 is 60 formed by a laterally extending loop intermediate the ends of the wire. The shield in this instance comprises a pair of expandible sections 63 and 64. Each section comprises a longitudinally extending elongated loop,

one length 65 of the loop 63 being connected to one length 66 of the loop 64 by the flanged loop 62. The other length of each loop is formed by the portion of wire having the laterally extending flange 60 or 61 at the end thereof.

70 As shown at 67, the wire at the inner end of each section is given a quarter turn or is flattened to partially close the loop.

In the form of the invention shown in Figs. 19 to 24 when an expanding element is driven 75 into the shield, the two sections will be forced laterally thereby into gripping engagement with the wall opening.

From the foregoing description, it will be seen that a simple and practical form of 80 shield construction has been designed and since the shield can be constructed by bending a single piece of wire, the cost of material and the labor necessary will be reduced to a minimum.

85 Although certain specific embodiments of the invention have been particularly shown and described, it will be understood that the invention is capable of further modification and that further changes in the construction 90 and in the arrangement of the various cooperating parts may be made without departing from the spirit or scope of the invention, as expressed in the following claims.

95 What I claim is:

1. A single piece expansion shield having a plurality of longitudinally extending expansible loop portions, each of said portions extending throughout the length of the shield, said portions having angularly disposed laterally extending flanges at one end thereof.
2. A single piece expansion shield formed of wire and having a plurality of longitudinally extending expansible loops and having angularly disposed laterally extending flanges at one end thereof.

3. An expansion shield having a plurality of expansible sections, each section comprising an elongated longitudinally extending loop closed at its inner end.

4. An expansion shield having a plurality of expansible sections arranged around a central opening, each section comprising an elongated longitudinal loop and having a flange at its outer end.

5. An expansion shield having a plurality of expansible sections arranged around a central opening, each section comprising an elongated longitudinal loop, said shield having radially extending flanges at the outer end thereof.

6. An expansion shield formed of wire and having a plurality of expansible sections, each section comprising an elongated longitudinal loop closed at its inner end.

7. An expansion shield formed of wire and having a plurality of expansible sections, each section comprising an elongated loop,

said shield having loops at the outer end thereof bent laterally to form angularly disposed flanges.

8. An expansion shield formed of wire and comprising a plurality of longitudinally extending wire loops closed at its inner ends.

9. An expansion shield formed of wire and comprising a plurality of longitudinally extending wire loops extending throughout the length of the shield, said shield having a plurality of laterally extending loops at the outer end thereof forming flanges.

10. An expansion shield formed of a single piece of wire and comprising a plurality of longitudinally extending wire loops.

11. An expansion shield formed of a single piece of wire and having a plurality of expansible sections, each section comprising an elongated longitudinally extending loop, said shield having laterally extending flanges at the outer end thereof.

12. In combination, an expansion shield formed of wire and having a plurality of expansible sections, each section comprising an elongated loop closed at its inner end, and an expanding element of greater length than the length of the shield whereby the element will engage and force laterally the inner ends of the loops.

13. In combination, an expansion shield formed of wire and having a plurality of expansible sections, each section comprising an elongated loop, said shield having laterally extending flanges at the outer end thereof, and a flanged expanding element of greater length than the length of the shield whereby the element will engage and force laterally the inner ends of the loops.

14. In combination, an expansion shield formed of wire and having a plurality of expansible sections, each section comprising an elongated loop closed at its inner end, and a drive expanding element of greater length than the length of the shield whereby the element will engage and force laterally the inner ends of the loops.

15. An expansion shield formed of wire and comprising a plurality of laterally expansible portions, each portion consisting of a loop closed at its inner end, and a plurality of radially disposed flanges at the outer ends of said shield.

16. A new article of manufacture comprising a wire expansion shield formed of wire bent back on itself to form a longitudinally extending bore, said bore being surrounded by a maximum of four parallel and longi-

tudinally extending strands of wire and having a wire head at an angle to the parallel strands of wire.

17. A new article of manufacture comprising a wire expansion shield formed of wire bent back on itself to form four parallel longitudinally extending strands of wire and an integral wire head formed in two parts.

18. In an expansion shield the combination of a wire shield formed by bending strands of wire back on themselves so that when expanded the shield will have a primary radial expansion in one direction, and a secondary radial expansion in a different direction, and an expanding member adapted to first cause the primary radial expansion in one direction on partial insertion of the expanding member, and cause the secondary radial expansion of the wire shield in a different direction on the complete insertion of the expanding member.

19. In an expansion shield the combination of a wire shield formed by bending strands of wire back on themselves to form parallel and longitudinally extending strands so that when expanded the shield will have a primary radial expansion in one direction, and a secondary radial expansion in a different direction, and an expanding member adapted to first cause the primary expansion in one direction on partial insertion of the expanding member, and cause the secondary expansion of the wire shield in a different direction on the complete insertion of the expanding member.

20. In an expansion shield the combination of a wire shield formed by bending strands of wire back on themselves so that when expanded the shield will have a primary radial expansion in one direction, and a secondary radial expansion in a different direction, and an ordinary nail adapted to first cause the primary expansion of the wire shield in one direction on partial insertion of the nail, and to cause the secondary expansion of the wire shield in a different direction on the complete insertion of the nail.

21. An expansion shield comprising a plurality of longitudinally extending expansible loops, each loop extending throughout the length of the shield and having its outer end bent laterally to form a flange, the flanges formed on the loops being angularly disposed relative to each other.

In witness whereof, I have hereunto set my hand this 29th day of November, 1924.

CHARLES C. TOMKINSON.
